DEVICE FOR THE MANUFACTURE OF
SHAPED PIECES FROM ANNULAR
BLANKS

Friedrich im Schlaa, Iserlohn, Germany

Application June 1, 1932, Serial No. 614,780
In Germany June 18, 1931

7 Claims. (Cl. 88—5)

In the manufacture of shaped pieces from annular blanks, it is known to use a rolling mandrel provided with a groove, which rolls out the work from the edges of the central hole or inner walls of a blank radially outwards producing slanting sides. In this rolling process the matrix in which the ring is rolled is mounted in such a manner that it can turn in a plane vertical to the axis of the rolling mandrel and can be moved nearer to the rolling mandrel in the same plane. As in all circumstances any seizure of the work by the mandrel must be avoided, the rolling surfaces must be disposed parallel or inclined to the axis of the rolling mandrel. With the use of the usual rolling process it was impossible to roll lateral faces disposed at right angles to the axis of the rolling mandrel, for instance for ball bearings, rings, and in particular it was impossible to produce shouldered bearing rings having one deep side or lateral surface even with the use of a rolling mandrel having flank surfaces at an obtuse angle to the axis of the rolling mandrel.

Now the subject of the present invention is a process for the manufacture of shaped pieces from annular blanks, wherein the work by means of a rotatable obliquely disposed matrix is held in a position oblique to the axis of the rolling mandrel, and during the rolling process is gradually moved (together with the matrix which forms one lateral surface) towards and against a rolling mandrel in a direction oblique to the centre axis of the matrix, and preferably vertical to the axis of the rolling mandrel, which by an oblique surface forms the second lateral surface, whereby the lateral surfaces, and if necessary also some of the inner surfaces of the work, are rolled vertically to its centre axis.

The apparatus used for carrying out the process has a lever member adapted to move vertically to the axis of the rolling mandrel, which lever member possesses a bearing surface disposed obliquely to the axis of the rolling mandrel, in which bearing surface the matrix is rotatably mounted. The lever member serving as matrix support is preferably pivoted at one end about a pin disposed parallel to the axis of the rolling mandrel, and at its other end engages,—if necessary with the interposition of a roller—with a cam controlling the travel of the matrix. To prevent displacement in the direction of the roller pressure the matrix is secured by retaining rings which, for the purpose of taking up the roller pressure on its inner surface and on

the side exposed to roller pressure, are provided with ball bearings, and are connected rigidly with the feed lever member.

In the process according to the invention the deeper lateral surface of the ring can be shaped by the matrix, while the other smaller lateral surface is formed by the rolling mandrel. The oblique arrangement of the mandrel makes it possible to roll very high and also non-uniformly high lateral surfaces which stand exactly at right angles to the axis of the ring.

One form of construction of the device for carrying out the process according to the invention is given, by way of an example, in the drawings, wherein:

Fig. 1 is a centre section of a shouldered bearing outer ring for ball bearings.

Fig. 2 shows the mounting and the arrangement of the shouldered bearing ring in a matrix standing obliquely to the axis of the rolling mandrel and the lever member controlling the feed travel in vertical cross section.

Fig. 3 is a side view of the lever.

Fig. 4 is a front view of the lever and the control shaft with cam.

Fig. 5 is a plan view of the rolling device showing the matrix support lever, the mandrel and the means for driving the latter.

The shouldered bearing outer ring shewn in the drawings is intended for a ball bearing such as is preferably used for mine wagons. The centre axis *a* of the ring *i* when being rolled stands at an angle to the axis *b* of the rolling mandrel *h* whose flank surface situated obliquely to the axis rolls the lateral surface *g* vertically disposed to the centre axis *a* or parallel to the median plane *d* of the ball bearing ring. During the rolling process, the ring *i* rotates in the median plane *d*, but at the same time is raised in a plane *e* vertically disposed to the rolling mandrel axis *b* whereby the necessary feeding movement is obtained.

The roller device shewn in Figs. 2—4 consists of a rolling mandrel *h* and a lever member *q* holding the matrix. At one end *n* the lever *q* is pivoted about the pin *j*, and the other end *m*, by means of a roller *t*, the height of which can be adjusted if necessary, engages with a cam *l* of a control shaft *s*, and thereby is raised gradually according to the desired feed of the material to be rolled. Whereas the ends *m* and *n* of the lever are at right angles to the axis of the rolling mandrel and at the same time form the lever guides, the middle part *r* is arranged obliquely to the axis of the rolling mandrel,

the oblique position being between the lines *o*, *p* shewn in Fig. 4. The middle piece *r* and with it the matrix *k* can be disposed obliquely to any desired extent, according to the shape of the 5 ring to be rolled.

The middle part *r* of the lever contains two 10 annular gripping jaws *u* and *v* on both lateral surfaces. These jaws are tightened by means of the screws *w* and enclose between them a ball bearing *x* rotating in the median plane *d* of the shouldered bearing ring and a matrix *k*, in which the shouldered bearing ring is placed. On the side subjected to rolling pressure there is 15 provided between the inner ring of the ball bearing *x* and the gripping jaws *u* an axial ball bearing *y* which ensures an easy movement for the matrix and the material to be rolled. The large lateral surface *f* and the peripheral surface *z* of the shouldered bearing outer ring *t* is formed 20 by the inner wall of the matrix *k*, whereas the narrow lateral surface *g* and the inner surface of the ring is formed by the rolling mandrel.

The mandrel *h* is coupled to a working spindle *c* by means of a non-rotatable, but longitudinally 25 movable sleeve *H* in which the roll mandrel cone *B* is secured by means of a compressive spring *A* acting on a shoulder *C* of the mandrel (Fig. 5). The working spindle *c* is driven by gear wheels *E*, *D* from the main shaft *F* of the machine 30 carrying a pulley *G*.

During rolling, the pivotally mounted rolling 35 mandrel *h* presses against the work *i*, and during rotation, by its pressure takes with it the work *i* and the matrix *k* rotating in the ball bearings. At the same time the lever *q* which 40 pivots about the pin *j* is raised by the cam *l* vertically to the rolling mandrel, until after attaining the desired travel the roller *t* passing over the shoulder of the cam allows the lever to fall. The ring rolled by the rolling mandrel into 45 exactly the desired shape is then ejected from the matrix *k* by an ejector device of known type, so that when new work has been inserted the rolling process can recommence.

Instead of moving the lever bearing the matrix 50 to the rolling mandrel, the rolling mandrel may be adapted to swing and the lever may be mounted rigidly, but it is important that there should be close contact between the matrix and the rolling mandrel, which alone makes rolling possible.

By means of the process according to the 55 invention it is also possible to work shouldered bearing rings of ball bearings with rolling surfaces partly vertical or substantially at right angles to the middle axis in a single operation, which was not possible by the rolling methods hitherto used. Moreover, perfectly smooth running surfaces can be obtained in a single operation 60 without subsequent turning of the recesses and instead of the hitherto usual conical lateral surfaces, it is possible to obtain lateral surfaces vertical to the middle axis, as any seizing of the rolling mandrel is avoided in the process according 65 to the invention.

I claim:

1. An apparatus for manufacturing ball races and the like comprising a rolling mandrel and a cooperating rotatable matrix both acting as 70 formers on a hollow work piece having parallel side faces, means for driving the mandrel, a lever having a bearing surface for the matrix and being adapted to swing about an axis parallel to the axis of the rolling mandrel, and means for 75 swinging the lever, the bearing surfaces of the

matrix and the working surfaces of the mandrel deviating at an angle to a plane at right angles to the axis of the mandrel.

2. An apparatus for manufacturing ball races and the like comprising a rolling mandrel and a cooperating rotatable annular matrix both acting as formers on a hollow work piece having parallel side faces, means for driving the mandrel, a lever having a bearing surface for the matrix, this bearing surface and the working surfaces of the mandrel deviating at an angle to a plane at right angles to the mandrel, a pin extending through a hole at one end of the lever to permit pivotal movement of such lever in a direction vertical to the axis of the mandrel, and a cam adapted to swing the other end of the matrix support lever towards the rolling mandrel.

3. An apparatus for manufacturing ball races and the like comprising a rolling mandrel and a cooperating rotatable annular matrix both acting as formers on a hollow work piece having parallel side faces, means for driving the mandrel, a lever having a bearing surface for the matrix, this bearing surface and the working surfaces of the mandrel deviating at an angle to a plane at right angles to the mandrel, a pin extending through a hole at one end of the lever to permit pivotal movement of such lever in a direction vertical to the axis of the mandrel, and a cam adapted to swing the other end of the matrix support lever towards the rolling mandrel, the side surfaces of the lever ends being adapted to guide the lever vertically to the axis of the mandrel.

4. An apparatus for manufacturing ball races and the like comprising a rolling mandrel and a cooperating rotatable annular matrix both acting as formers on a hollow work piece having parallel side faces, means for driving the mandrel, a lever having a bearing surface for the matrix, this bearing surface and the working surfaces of the mandrel deviating at an angle to a plane at right angles to the mandrel, a pin supporting one end of the lever for pivotal movement in a direction vertical to the axis of the mandrel, a cam, a roller adjustably mounted in the other end of the lever and engaging said cam, said cam operating to swing the matrix support lever towards the rolling mandrel, the side surfaces of the lever ends being adapted to guide the lever vertically to the axis of the mandrel.

5. An apparatus for manufacturing ball races and the like comprising a rolling mandrel and a cooperating rotatable annular matrix both acting as formers on a hollow work piece having parallel side faces, means for driving the mandrel, a cam-controlled pivoted lever having a swinging axis parallel to the mandrel and a bearing surface for the matrix, this bearing surface and the working surfaces of the mandrel deviating at an angle to a plane at right angles to the mandrel, a retaining ring in the lever adapted to secure the matrix against lateral displacement, and ball bearings provided on the periphery of the matrix and at one side face for sustaining the rolling pressure.

6. An apparatus for manufacturing ball races and the like, including a rolling mandrel and a cooperating rotatable matrix acting as formers on a hollow work-piece, means for driving the mandrel, a support for the matrix movable about an axis parallel to the axis of the mandrel, and means for moving the support, the plane of

rotation for the matrix and the working surfaces of the mandrel being at an angle other than right angles to the axis of the mandrel.

7. An apparatus for manufacturing ball races and the like, comprising a rolling mandrel, a cooperating rotatable annular matrix to receive and support a hollow work-piece with which the mandrel cooperates, means for driving the mandrel, a support for the matrix, a member

in which the support is rotatably mounted, said member being adapted to swing about an axis parallel to the axis of the mandrel, and means for swinging the member, the plane of rotation of the matrix and the working surfaces of the mandrel being at an angle to a plane other than right angles to the axis of the mandrel.

5 FRIEDRICH IM SCHLAA.
